APPARATUS FOR MOVING AND MINING MATERIAL OF A GRANULAR
AND COMMINUTED NATURE.

APPLICATION FILED JULY 25, 1902.

2 SHEETS—SHEET 2.

UNITED STATES PATENT OFFICE.

ALEXANDER McDougall, OF DULUTH, MINNESOTA.

APPARATUS FOR MOVING AND MINING MATERIAL OF A GRANULAR AND COMMUNICATED NATURE.

No. 821,872.

Specification of Letters Patent.

Patented May 22, 1906.

Application filed July 25, 1902. Serial No. 116,919.

To all whom it may concern:

Be it known that I, ALEXANDER McDougall, a citizen of the United States, residing at Duluth, in the county of St. Louis and State of Minnesota, have invented certain new and useful Improvements in Apparatus for Moving and Mining Material of a Granular and Communited Nature, of which the following is a specification.

This invention relates to apparatus for moving and mining material of a granular and communited nature—such as coal, iron ore, or other kinds of granular mineral, marl, &c.—which sometimes occurs in nature as a bed disposed below a layer of earth or sand of varying thickness and is an improvement on the method and means described in my prior patents, Nos. 619,601, 657,247, 531,740, 547,496, and 604,628. This material is sometimes found mixed with a large percentage of water and, as far as I know, has heretofore been mined by mechanical means in the following manner: A shaft or shafts are sunk through the earth to the bed of material, and radial galleries are cut through this material, portions of it being left at intervals to form supports for the upper crust of earth, the material being carried to the shaft-base in cars and hoisted to the surface in buckets. If the crust of earth be not thick enough to be readily supported, it is removed by means of an excavator or some such similar device and the bed of minable material exposed. This material may then be mined by means of the same excavator. Pumps are provided to withdraw the accumulation of water. The machinery required for this form of mining is very expensive and being heavy and bulky is costly to transport to the mines. Furthermore, such mines, usually being located at present in sparsely-settled country, repairs to machinery are difficult, slow, and expensive. These mines usually occur in a moderately level country, where attempts to use the ordinary method of hydraulic mining are impossible, owing to the lack of sufficient head of water.

My method generally is as follows: The deposit of material being located, elevated ground convenient thereto is selected as a base of deposit for the excavated material. Railway-tracks are laid convenient to this point, and means are provided for loading the material upon cars. Another point at a convenient distance, but at a slightly lower elevation, is selected as a location for a reser-

voir. A place is excavated in the soil of sufficient depth and area to form a pond to contain water enough for all uses. Adjacent to this reservoir a shaft is sunk through the earth to the bed of material to be mined, and a sump or pit is made in the bottom thereof. In case the minable material is directly exposed a shaft or pit of slight depth is first sunk and the sump then made in the bottom thereof. A pipe is provided and connected with the reservoir and is used to supply water at a sufficient pressure at the bottom of the pit, preferably a flexible pipe and nozzle, as in ordinary hydraulic-mining practice, being used. The material is loosened and dissolved by the stream of water and is carried in suspension to the sump, which is preferably covered by a screen to prevent entrance of large lumps of material, and from there it is elevated, by means of a pump located in the pit, through a pipe to the place of deposit. The water therefrom will drain away and be returned by means of a canal or flume to the reservoir. Ordinarily the mined material will contain more than a sufficient amount of moisture to make up for the loss of water by evaporation and seepage, the surplus being allowed to overflow from the reservoir. If the crust of earth covering the bed of material be not thick enough to justify galleries being run, it will be removed over as much of the bed as is to be mined. This removal may be accomplished in the same manner as the other material is mined, a proper location for the earth being secured separated from the pile of mined material.

In some instances it may be found impossible to get a sufficient head of water in the excavating-pipes to properly force the stream against the material and break it up. This difficulty may be overcome by using an additional pipe and force-pump, which may be located adjacent to the reservoir or close to the nozzle or intermediate thereto. It may be found advantageous in practice to locate the force-pump alongside of the excavating-pump, driving both by the same power. A force-pump would be of great service in excavating the top soil or when the bed of minable material is situated at a slight depth.

In order to better understand the nature of my invention and the means whereby it may be carried out, attention is called to the accompanying drawings, in which—

Figure 1 is a section through a pit, dump, and tank. Fig. 2 is a top view thereof, and

Fig. 3 a section through a pit, shaft, tank, and dump wherein the top soil is somewhat thicker than that shown in Fig. 1; and Fig. 4 is a view of a modification.

5 In all the several views like parts are designated by the same characters of reference.

The deposit of valuable mineral or material 1 is shown as lying below a comparatively thin layer of valueless material 2 in Fig. 1, 10 but under a somewhat thicker layer in Fig. 3. The apparatus is modified as is necessary, as shown in the two views, as depends upon the character and thickness of the layer of valueless material. If it is comparatively thin or 15 is composed largely of loose earth, gravel, or sand, it is necessary to excavate a pit or crater, as at 3. If the layer be thick or formed of dense earth, a shaft 21, with an enlarged base 22 and galleries 24, with material left at 20 intervals to form supporting-pillars 23, may be made. The pit or shaft is sunk adjacent to ground of higher level, upon which may be dumped the valuable material 4 directly into a car 4', if desired, (see Fig. 4,) with a second 25 pit at a slightly lower level to form a tank or reservoir 5. In the bottom of the pit is excavated a smaller pit or sump 6. The relative 30 levels of dump, tank, and sump are indicated by the letters of reference A, B, and C, respectively. In practice the tank 5 will be at but slightly lower level than the dump, while the sump will be as low as possible in order to get a sufficient head of water for excavating. The water-supply pipe 7, with a flexible ex- 35 tremity 8, nozzle 9, and valve 10, is connected with the tank 5 and supplies a sufficient head of water to wash the material to be excavated into the sump 6. This material, carried in suspension with a relatively large bulk 40 of water, is removed by means of a pipe 11. A perforated plate or screen 12 is used to prevent ingress of too large pieces of solid material, such as might choke the pump.

The mixture of material and water is elevated to the dump 4 by means of the centrifugal pump 13 and discharged at 14. To assist the action of the pump 13 in very deep pits or shafts, an additional centrifugal pump 15 may be employed and the number increased *ad infinitum*, the lower pumps forcing the material up for action of the pumps above. I have found in practice that there is no centrifugal pump on the market that is able to lift the mixture of water and material 55 a greater distance than twenty-two feet, but the limit to which the same mixture may be forced is much larger. It is of great advantage to locate the pump adjacent to the sump, as it is difficult to prime a centrifugal pump, 60 and foot-valves are of but little or no use when a mixture of water and earth is being operated upon. I therefore lay great stress upon the advantage of locating the excavating-pump in the bottom of the pit for the

above-stated reasons. There may be instances in practice where the "tailings-dump" is at such a distance from the pit that a single pump will not be able to force the material. I therefore provide the arrangement illustrated in Fig. 4, in which additional 65 centrifugal pumps 15' 15' are used.

In some instances the level of the tank 5 at B is sufficiently elevated above the sump 6 at C to secure the proper head. To increase the pressure of the water at the nozzle 75 9, another pipe and a force-pump 16 may be used. Both pumps 16 and 13 may be driven by the motor 17 through the agency of the shaft 18 or separately. The motor may be operated by steam, compressed air, or electricity, as is preferred. The water from the valuable-material dump 4 is pumped to or drains into the tank 5 through the canal 19. Any excess of water in the tank may overflow and be conducted away through a sluice or 85 canal. (Not shown.)

For the purpose of cutting off the supply of water while the pipe 8 is being repaired, adjusted, or renewed an additional valve 20, operated from the surface of the ground, may 90 be employed.

It is necessary that the pump 13 be of sufficient capacity to effectively remove all water from the sump 6. This water may directly flow over the surface of the pit or may 95 be the result of seepage from the surrounding locality.

My apparatus is operated in the following manner: The deposit of material having been located and the place for the tailings-dump 100 located, the tank 5 and connecting-canal 19 are dug. The pit 3 or shaft 21 is then excavated. This may be entirely by direct mechanical means or it may first be started by 105 mechanical means and the hydraulic appliance brought into operation. The pipes and pumps are arranged as also described. There will usually be found enough water in the soil or bed of material caused by seepage from the adjoining soil to partly fill the reservoir 5. 110 If there is an insufficient amount, water must be supplied from some other source. The hydraulic jet is caused to play upon the walls and base of the pit, the mixture of water and solid material that drains into the dump being removed by the pump 13 and deposited upon the valuable-material dump. In the preliminary part of the operation the pump 13 may eject a mixture of valueless material 115 with the water. This may be directed by the pump to a spot somewhat removed from the valuable-material dump, so as not to mix with the valuable material when excavated. When the bed of valuable material is reached, the stream of water from the nozzle 9 is directed exclusively thereupon, so that it may 120 be carried in suspension with water into the sump and from there be ejected by the pump. 125

The water for the valuable material will pass into the tank through the canal 19, and if too much of it escapes to lower ground it is pumped back to the reservoir. When the 5 depth or other characteristic of the surface soil justifies it, galleries 24 may be extended through the material, additional length being added to the pipes 7 or 8 to allow a stream of water being introduced into the galleries. 10 If the ejected material is found mixed with sand or other foreign matter, suitable means may be employed to separate the same, such means being well known to those skilled in the art.

15 Having described my invention, what I claim, and desire to secure by Letters Patent, is—

1. In an apparatus for raising valuable material which lies in a layer at considerable 20 depth below a layer of valueless material, the combination of the layer of valueless material having an opening therethrough and exposing the layer of valuable material, the 25 said layer of valuable material having a chamber formed therein, and a sump within the chamber, columns or pillars sustaining the roof of the chamber, a reservoir formed on the layer of valueless material, a pipe or 30 pipes connecting said reservoir and passing through the layer of valueless material and entering the chamber within the layer of valuable material, means for directing a stream or streams of water from said pipe or pipes against the valuable material, a lift pump or 35 pumps within the chamber and having its or their inlet or inlets within the sump and discharging out through the opening in the layer of valueless material upon a dump formed upon the layer of valueless material, and a canal 40 connecting the dump to the reservoir whereby the same water may be used for disintegrating the valuable material, carry-

ing it in suspension to the sump and discharging it to the dump.

2. In an apparatus for raising valuable 45 material which lies in a layer at considerable depth below a layer of valueless material, the combination of the layer of valueless material having an opening therethrough and exposing the layer of valuable material, the 50 said layer of valuable material having a chamber within it and of greater extent than the opening in the layer of valueless material and immediately below said opening, a sump within the chamber, columns or pillars 55 formed within the valuable material and sustaining the roof of the chamber in the layer of valuable material, a reservoir formed on the layer of valueless material, a pipe or pipes 60 connecting said reservoir and passing through the opening in the valueless material and entering the chamber within the layer of valuable material, means for directing a stream or streams of water from said pipe or pipes against the valuable material, a lift pump or pumps 65 within the chamber and having its or their inlet or inlets within the sump and discharging out through the opening in the layer of valueless material upon a dump formed upon the layer of valueless material, and a canal 70 connecting the dump to the reservoir whereby the same water may be used for disintegrating the valuable material, carrying it in suspension to the sump and discharging it to the dump, and whereby an opening in the 75 layer of the valueless material of the smallest size will be formed.

This specification signed and witnessed this 12th day of July, 1902.
